UNITED STATES PATENT OFFICE.

ALBERT H. LEWIS, OF UHRICHSVILLE, OHIO, ASSIGNOR OF THREE-FOURTHS
TO ALBERT G. QUIMBY, JAMES C. SHIELDS, AND PETER C. STEVENSON,
OF UHRICHSVILLE, OHIO.

BOLT AND FASTENER THEREFOR.

SPECIFICATION forming part of Letters Patent No. 708,486, dated September 2, 1902.

Application filed May 20, 1902. Serial No. 103,227. (No model.)

To all whom it may concern:

Be it known that I, ALBERT H. LEWIS, a citizen of the United States, residing at Uhrichsville, in the county of Tuscarawas and State 5 of Ohio, have invented new and useful Improvements in Bolts and Fasteners Therefor, of which the following is a specification.

My invention relates to improvements in bolts and means for fastening the same in 10 position; and it consists in a certain peculiar and advantageous bolt and bolt-fastener designed more especially for use in railway-rail joints, as will be hereinafter fully described and claimed.

15 In the accompanying drawings, Figure 1 is a side elevation of a rail-joint embodying my improvements; Fig. 2, an enlarged transverse section taken in the plane indicated by the broken line 2 2 of Fig. 1 and showing the improved bolt in elevation; Fig. 3, an enlarged perspective view of the improved bolt removed, and Fig. 4 a similar view of the bolt-fastener.

Similar letters of reference designate corresponding parts in all of the several views of the drawings, referring to which—

20 A A are the meeting ends of two railway-rails, which are preferably provided in their webs with the usual oblong apertures a to permit of expansion and contraction; B, a fish-plate or splice-bar disposed at one side of the rails and having apertures b coincident with the apertures a thereof; C, a splice-bar or fish-plate disposed at the opposite side of 30 the rails with reference to plate B and extending by preference up at the side of the rail-heads to points flush with the treads thereof and provided with transverse apertures c coincident with the apertures a; D D, 35 bolts constructed in accordance with my invention and extending through the registered apertures of the fish-plates and rails, and E E bolt-fasteners, also constructed in accordance with my invention. The bolts D are similar 40 in construction, and therefore a detailed description of the one shown in Figs. 2 and 3 will suffice to impart an understanding of all. Said bolt is provided at one end with the usual head d, and adjacent to said head 45 50 it has a lug e, designed to seat in a comple-

mentary offset of the aperture b, with a view of holding the bolt against turning on its axis. Adjacent to its opposite end and in its upper side the bolt is provided with a cross-wise kerf or groove f, the outer wall g and bottom wall h of which are by preference slightly undercut and inclined downwardly and inwardly, respectively, as shown. 55

All of the bolt-fasteners E are similar in construction to and are applied in the same 60 manner as the fastener E shown in Figs. 2 and 4. Said fastener E is formed of one piece of suitable metal and has side walls i, joined by an outer end wall j and preferably by a top wall k. The said side walls i have 65 convex serrated or toothed inner ends l, and the top wall k when employed also has a serrated inner end l', designed to engage the plate C, while the end wall j has a pointed toe m, adapted to enter the groove f of the 70 bolt D and bear against the wall or abutment g after the manner shown in Fig. 2.

In applying the improvements the bolt D is placed in registered apertures of the fish-plates and rail, so that it projects a considerable distance beyond the plate C, and the fastener E is arranged with its toe m in the groove f of the bolt and its convex serrated end bearing against the plate C. When the fastener is disposed as stated and its serrated 80 end is pressed downwardly, it will be observed that the bolt will be drawn tight and securely fixed in position; also, that when trains pass over the joint the jar will tend to work the serrated end of the fastener downwardly and 85 cause it to further tighten or take up looseness or lost motion of the bolt due to wear. The serrated end of the fastener engaging the side of the fish-plate C holds the fastener against casual upward movement, and hence 90 effectually prevents casual loosening of the connection between the rail and fish-plates.

I have shown the joint as embodying four bolts and four fasteners; but it is obvious that any desired number of bolts and fasteners may be employed in a joint without departing from the scope of my invention. I also desire it understood that while designed more particularly for use in rail-joints my improved bolt and fastener may be used in 95 100

other connections to which it is applicable with advantage.

Having described my invention, what I claim, and desire to secure by Letters Patent, 5 is—

1. A bolt having a crosswise abutment thereon adjacent to one end, in combination with a fastener adapted to bear at one end against the crosswise abutment of the bolt, and having an opposite convex and serrated or roughened end to engage a device through which the bolt is passed.

2. A bolt having a crosswise groove adjacent to one end, the outer wall of which is undercut and constitutes an abutment, in combination with a fastener having a toe at its outer end and adapted to bear in the groove, and also having a convex and serrated or roughened inner end adapted to be pressed into engagement with a device through which the bolt is passed.

3. A bolt having a crosswise abutment thereon, undercut at its inner side, in combination with a separate fastener having a pointed toe at its outer end adapted to bear in the undercut of the abutment, and an inner end adapted to engage a device through which the bolt is passed. 25

4. The combination of a bolt having a crosswise groove, the outer wall of which is undercut, and a fastener having the side and top walls, and also having the toe at its outer end disposed in the crosswise groove of the bolt, and its inner end rounded and roughened or serrated. 30

In testimony whereof I have hereunto set my hand in presence of two subscribing witnesses.

ALBERT H. LEWIS.
